PACKING TRAY FOR FRAGILE ARTICLES

Richard L. Emery, Fairfield, Maine, assignor to
Keyes Fibre Company, Portland, Maine, a corporation of Maine

Application July 28, 1953, Serial No. 26,163

Term of patent 14 years

(Cl. D58—13)

To all whom it may concern:

Be it known that I, Richard L. Emery, a citizen of the United States of America, residing at Fairfield, county of Somerset, State of Maine, have invented a new, original, and ornamental Design for a Packing Tray for Fragile Articles, of which the following is a specification, reference being had to the accompanying drawing, forming part thereof.

Fig. 1 is a plan view of a packing tray for fragile articles showing my new design;

Fig. 2 is a sectional view thereof taken along the line 2—2 of Fig. 1; and

Fig. 3 is a sectional view thereof taken along the line 3—3 of Fig. 1.

I claim:

The ornamental design for a packing tray for fragile articles, as shown.
